J. MASSON.
OVEN ILLUMINATOR.
FILED OCT. 25, 1921.

INVENTOR
J. MASSON

BY *Wright McCrum*

ATTRAYS:

UNITED STATES PATENT OFFICE.

JOHN MASSON, OF SAN FRANCISCO, CALIFORNIA.

OVEN ILLUMINATOR.

Application filed October 25, 1921. Serial No. 510,251.

To all whom it may concern:

Be it known that I, JOHN MASSON, a citizen of the United States, residing at San Francisco, in the county of San Francisco 5 and State of California, have invented new and useful Improvements in Oven Illuminators, of which the following is a specification.

The present invention relates to improvements in cook stoves or ranges and has particular reference to means for illuminating the oven chambers of said stoves or ranges.

The back of the oven chamber of the ordinary cook stove or range is usually dark, 15 making it difficult to obtain a clear view of the rear part of the chamber and often requiring the use of some means of illumination when it is desired to view the back of the oven. Accordingly the primary object 20 of this invention is to provide a novel means for illuminating the oven chamber of a stove with the light derived from the fire in the stove.

A further object of the invention is to 25 provide simple and inexpensive means for illuminating the oven chamber of a stove, which means may be readily and easily incorporated with a cook stove and is arranged so that the oven may be illuminated 30 at will and viewed when the door is closed or opened.

The invention possesses other advantages 35 and features some of which, with the foregoing will be set forth at length in the following description where I shall outline in full that form of the invention which I have selected for illustration in the drawings accompanying and forming a part of the present specification. In said drawings 40 I have shown one form of the construction of my invention, but it is to be understood that I do not limit myself to such form since the invention as expressed in the claims may be embodied in a plurality of 45 forms.

Referring to the drawings:

Fig. 1 is a view partly in section and partly in elevation of a stove constructed in accordance with my invention.

Fig. 2 is a horizontal sectional view taken on line 2—2 of Fig. 1.

Fig. 3 is a perspective view of one of the elements of the invention.

Referring particularly to the drawings, 1 55 designates a cook stove of the type adapted for burning coal or wood, or oil wherein

there is provided the usual fire box 2 contiguous with an oven chamber 3, the latter having the customary door 4.

In carrying out my invention I provide a 60 construction which will permit of the passage of the light from a fire in the fire box into the oven chamber, thru the wall or partition separating the fire box from the chamber. In practice, I preferably form in 65 said wall or partition, which latter is designated 5, an opening or a series of openings 6, preferably the latter, the said openings being located adjacent the upper side of the oven chamber and towards the rear thereof. 70 In case of a series of openings, said openings will be arranged in a horizontal row, the main requirement being that sufficient of an opening be provided to permit the necessary light to enter the chamber so as 75 to provide for properly illuminating the same.

In order to prevent the dust, ashes, cinders and the like from entering the oven chamber thru the openings 6, I provide a 80 guard member 7 which is in the form of a plate and is mounted within the fire box 2 so as to extend from the top of the partition wall 5 down to the level of the floor of the ash-pit 8, in close but spaced relation to said 85 wall 5. Preferably the upper end of this guard member 7 is curved as at 9 so that it will contact with the upper portion of said wall 5, whereas, the remaining portion of the guard is spaced throughout from said 90 wall. The guard is provided adjacent its upper edge with a series of openings 10 which register with the openings 6. Below the series of openings 6 there is provided another opening or a series of openings 11, 95 the upper portion of which will register with the openings 6. The guard plate may be formed with openings of any character and arrangement, provided that said openings will permit of the light from the fire 100 to pass therethru, thru the openings 6 and into the oven chamber. The guard member 7 in being spaced from the wall 5 and having a curved part 9 in which the openings 10 are formed, will cause the soot, ashes 105 and the like, having a tendency to fall, to drop thru the openings 10 and fall into the ash-pit in the space between the front and wall 5. Accordingly the lower edge of the plate is cut away as at 13 so as to permit 110 of the ashes and the like to sift into the pit 8. This arrangement prevents the openings

6 from becoming clogged with ashes, cinders and the like and insures the passage of light rays thru the openings 6 and into the oven. Although not shown in the drawings, the ordinary stove fire box is provided with a wall of thick cast iron between the thin partition wall 9 and fire box, so as to prevent the burning out of the thin sheet metal partition. In carrying out my invention, I substitute for this protecting wall the guard plate 7 which serves the purpose of said wall and has its own function with relation to this invention.

To control the illumination of the oven there is provided a slide member 13' arranged in the manner of a damper and mounted upon guides 14 within the oven chamber. This member 13' is formed with openings 15 adapted to be moved into and out of registration with the openings 6. The sliding of the member 13 is effected thru a rod or similar element 16 which extends out from said member 13 thru an opening or recess 17 formed in the frame 18 for the door 4, there being a nob 18' on the outer end of the rod so that it may be grasped in manipulating the slide. The openings 15 are closed by transparent panes 19 formed of glass or isinglass so as to exclude the smoke and products of combustion from the oven chamber.

For the purpose of viewing the interior of the oven when the door is closed, there is provided a peep hole 20 in the upper edge of the door, which hole is preferably closed by metal or other opaque swinging closure 21. The closure may be lifted or moved so as to uncover the peep hole at will. The hole 20 has a glass or isinglass pane 22 therein.

It will thus be seen that when a stove is equipped with illuminating means of my invention, it is only necessary to grasp the slide rod and manipulate the same so as to cause the openings 15 in the slide to register with the opening 6 and the light from the fire in the fire box will enter and illuminate the oven whereby a thorough view of the entire oven chamber may be had. If it is desired not to open the door to obtain such a view, thorough view may be had by looking thru the peep hole.

I claim:

1. The combination with a stove having a fire box and an oven chamber, of a wall separating said fire box and oven chamber, means providing for illumination of the interior of the oven chamber with the light reflected by a fire in said fire box and excluding smoke and ashes from the fire box and

means providing for the entrance of the light into or the exclusion thereof from the oven chamber at will.

2. A cook stove having an oven chamber, a fire box, and a wall separating the chamber and fire box, said wall having an opening therein covered by a glass pane arranged to permit light from a fire in the box to enter and illuminate the oven chamber and excluding smoke and ashes from the oven.

3. A stove comprising an oven chamber, a fire box, a door closing said oven chamber and having an opening therein thru which the interior of the oven may be viewed, a wall separating the fire box and oven chamber and provided with an opening arranged to permit light from the fire in said box to enter and illuminate the chamber and a transparent covering for the last named opening.

4. A stove comprising an oven chamber, a fire box, a door closing said oven chamber and having an opening therein thru which the interior of the oven may be viewed, a wall separating the fire box and oven chamber and provided with an opening arranged to permit light from the fire in said box to enter and illuminate the chamber and a shutter normally closing the opening in said door and glass panes in the shutter openings.

5. The combination with a stove having an oven chamber, a fire box, a wall separating the oven chamber and fire box, said wall having an opening therein located and arranged to permit light from a fire in the box to enter and illuminate the oven chamber of a slide member for opening and closing said opening to regulate the illumination of the oven chamber and a guard plate mounted within the fire box in close but spaced relation to said wall and having an opening therein registering with the opening in said wall.

6. The combination with a stove having an oven chamber, a fire box, a wall separating the oven chamber and fire box, said wall having an opening therein located and arranged to permit light from a fire in the box to enter and illuminate the oven chamber, of a slide member for opening and closing said opening to regulate the illumination of the oven chamber and a guard plate mounted within the fire box in close but spaced relation to said wall and having an opening therein registering with the opening in said wall, the upper edge of said guard being directed inwardly so as to engage the wall adjacent the upper edge thereof.

JOHN MASSON.
